COMBINED GATE AND RISER

Morris Bean, Yellow Springs, Ohio

Application August 1, 1940, Serial No. 349,033

9 Claims. (Cl. 22—134)

This invention relates to the art of metal casting and more particularly to novel structures combining a pouring gate and a riser in connection with metal casting molds.

In making a metal casting by filling a mold with liquid metal there are certain principles which are used in order that the finished casting may be made of sound, clean metal.

In order that the metal may be sound it is necessary that the familiar change in volume with change of state be compensated for. In almost all of the commercial alloys there is a decrease in volume accompanying the change from the liquid to the solid state. In order to prevent this phenomenon from leaving unsound and spongy sections in the casting it is necessary that a reservoir of liquid metal be available as the casting freezes, and that this be connected to the casting in such a way that, immediately after the mold cavity is full, the casting freezes progressively toward this reservoir, or "riser." The riser, of course, must be the last to freeze off. Liquid metal, when it is available, will flow into the intercrystalline cavities of contiguous metal which is freezing off and "feed" it, thus preventing any difficulty from "shrinks."

This principle may perhaps be made more clear by presenting it as follows: If an irregular mold cavity is filled with metal which shrinks on freezing, and the metal is allowed to freeze, the heaviest sections of metal, which are the last to solidify, will be full of characteristic shrinkage cavities. In the method with which I am here concerned a sound casting is assured by making this shrinkage occur outside the casting proper, that is, by putting it in a riser. This riser must be attached directly to the casting or by a heavy connector. If too light a connector is used it will freeze off before the casting proper, and the riser will not have an opportunity to perform its function. To the same end the riser preferably should be located and designed so that the hottest metal is in the riser. This metal, preferably, should not be allowed to run through the mold or other passages where it would be cooled by exposure to the walls.

It is obvious, therefore, that a very large proportion of the metal poured into a mold does not go into the casting proper, but into accompanying necessary gates, risers, and runners; and very worthwhile economies are realized according to my invention when the ordinary gates and risers are replaced by something equally effective, but requiring the use of substantially less metal.

Accordingly, it is an object of the invention to effect important economies by reduction of the amount of metal required for pouring each casting, thus reducing melting costs and also the proportion of metal which must be cut from the casting in the form of gates and risers and subjected to remelting, with the usual concomitant losses and deteriorations.

Another object of the invention is to produce uniformly sound castings of high quality. Another object of the invention is to simplify the pouring and gating of molds for casting.

Another object of the invention is to provide a pouring gate which will effectively skim the metal cast into the mold.

Another object of my invention is to so design a gating arrangement that the metal occupying the downpour gate when the mold is full will function integrally with that in the riser to feed the casting as it freezes.

Another object of the invention is to effect important economies by reduction of the amount of metal required for pouring each casting and thus reducing melting costs and scrap losses.

Other objects of the invention will appear from the following specification and the accompanying drawings.

In the preferred embodiment of my invention, I provide a combined gate and riser unit which may be assembled and used as a unit and applied to various molds.

A gating arrangement which has the basic essentials for making sound clean castings has (1) a down-pour gate; (2) passage from the gate into the mold cavity having a choke or skim bob, this passage designed, wherever possible, to allow the metal to run into the bottom of the mold and rise therein, thus preventing turbulence with accompanying trapped air and formation of oxide films; (3) a riser connected directly to the mold cavity through a wide passage; and (4) the riser and the passage so related to the mass of metal in the riser as to avoid freezing of the metal in the riser and in its connection to the casting until after the freezing of the casting itself.

In the accompanying drawings I have shown a preferred embodiment of my invention, and in the following specification I shall suggest various modifications thereof. It is to be understood that these are not intended to be either exhaustive or limiting of the invention, but on the contrary are chosen for the purpose of illustrating the invention, in order that others skilled in the art may so fully understand the inven-

tion, its principles and the application thereof that they may embody it and adapt it in numerous forms, each as may be best suited to the requirements of its particular use.

In these drawings:

Fig. 1 is a view in vertical section taken through the combined gate and riser and portion of the connected mold;

Fig. 2 is a top plan view of the unit of Fig. 1;

Fig. 3 is a vertical section taken on line 3—3 of Fig. 2;

Fig. 4 is a sectional view similar to that of Fig. 1, but showing a modified unit embodying the invention;

Figs. 5 and 6 are diagrammatic sectional views showing in comparison the metal necessary outside of the mold in the conventional practice and according to my invention respectively;

Figs. 7 and 8 are views similar to Figs. 1 and 3 respectively, but showing another modified form of the invention;

Fig. 9 is a fragmentary view in horizontal section showing a twin mold embodying the invention; and

Fig. 10 is a view similar to Fig. 9, showing a multiple mold embodying my invention.

Referring first to Figs. 1 to 3 inclusive, I have shown at 10 a fragmentary portion of a plaster mold designed, for example, for casting aluminum or bronze. At the end of this is an opening 11 through which the molten metal is fed into the mold cavity 12. A cavity of the size shown will ordinarily be provided with a core 10'. Connecting with the opening 11, I have formed the end of the mold with a recess 13, which in this case constitutes a part of the combined gate and riser when the mold is assembled with the gate and riser unit as more fully described below.

The gate and riser unit shown in pouring position in these figures consists of two separate channel portions 14 and 15, forming the outer portion of the riser and gate respectively and the former adapted to register with and form a continuation of the recess 13. The portions 14 and 15 are made of a refractory insulating material. In most cases I find it advantageous to make these of a porous fully calcined plaster or other material with relatively high insulating value.

These channel parts 14 and 15 are held together in assembled relation and given additional strength to resist the weight and impact of the poured metal, and protect them against clamping forces and shocks to which they may be accidentally subjected, by the sheet metal sections 16—17 clamped together to form a casting for the combined gate and riser by means of the U-clamps 18, which are made of resilient steel and driven over the projecting edges of the casing members 16—17.

Clamped between the members 14—15 and in this case extending between the sheet metal sections 16—17 is a separator 19 of a refractory sheet material, preferably of an insulating nature so that it does not conduct heat away from the mass of metal in the gate and riser unit. I have found it advantageous to use for this separator 19 a sheet of asbestos paper. Near the bottom of this separator 19 is a relatively small opening 20 through which the metal must pass from the pouring gate into the riser and before passing into the mold; thus, this partition 19 acts as a skimmer or choke to keep the metal clean and to hold back any dross or oxides, etc., which

may collect on the surface of the molten metal and flow with it into the pouring gate.

In the use of this device the metal is poured into the funnel at the upper end of the pouring gate channel member 15 through which it flows down behind the separator 19 and through the opening 20 into the riser channel 13 and thence into the opening 11 and finally into the mold cavity 12. As the metal rises in the mold cavity, it rises, of course, correspondingly in the riser channel 13—14. When the mold is finally filled and the pouring stopped the level of the metal will be at the same height on both sides of the separator 19 and advantageously close to the top of the channels 14 and 15 so as to provide a "head" or hydraulic pressure on the metal within the cavity 12.

As the metal within the mold cavity 12 chills and freezes, its contracts, as already described above. So long as the metal in the riser channel 13—14 and in the opening 11 remains molten and connected with the casting by a channel of molten metal, such metal will be available to "feed" the inter-crystalline cavities of the metal as it freezes off, and thus spongy portions and other imperfections in the casting can be avoided.

Due to the relatively large opening shown at 11, and due to the fact that this opening 11 is surrounded by molten metal, both on the inside and the outside of the mold, the metal in the opening 11 does not freeze until after the casting; and likewise, due to the insulation of the column of metal in the combination pouring gate and riser unit, metal in the riser does not freeze until after the casting and the connector 11.

I should like particularly to emphasize that with my arrangement the metal finally occupying the riser is the hottest present. This is true for two reasons: (1) this riser is finally filled up with the last metal to be poured from the ladle, and (2) the metal in the riser has been cooled off by flowing through any portion of the mold. Also, with my arrangement it is possible to first introduce the metal into the mold through a low opening therein, and let it rise gently in the mold cavity, thus preventing the entrapping of air and the formation of oxide films which are the results of turbulence.

I find that my castings are extraordinarily clean and free of dross because the metal is so effectively skimmed by flowing through the slots I have provided.

It is important in obtaining these results that the riser and the gate are, as shown in the drawings, in close heat-exchange relation and together are insulated from the outside atmosphere. As a result of this arrangement, the hot metal flowing into the pouring gate tends to preheat the combined unit and, therefore, to keep hot the metal which collects within the riser. Moreover, the heat carried by the last metal poured into the pouring gate is added to the heat of the metal in the riser itself, thereby serving to delay the final freezing of the metal in the riser; and, once the pouring is stopped, the two channels continue to act together as a single riser and in this way the metal left in the pouring gate replaces metal which otherwise would have to be accumulated in the riser and the total amount of metal poured for each casting is thus substantially reduced with corresponding reductions in melting costs, in the capacity of melting and pouring equipment required, in the number of castings which can be made in one pouring and in the losses and de-

teriorations which occur upon reclaiming and remelting of the gates and risers. Moreover, the recovery of the gates and risers and their removal from the final casting is simplified. Thus, by the use of this invention there results at once very substantially reduced cost and improved quality of casting.

In Fig. 5, I have illustrated graphically the saving achieved by my gate and riser combination over a typical conventional arrangement. The closely cross hatched area shows in cross section the amount of extra metal needed to fill the conventional arrangement which is saved by my present invention.

In Fig. 1, as described above, I have used a recess in the outer surface of the mold itself to serve as a part of the riser channel. When the mold is of a suitable refractory material, as for example, in the case of the ordinary plaster mold most commonly used prior to my invention, this may be found most economical and convenient; but my invention is not limited to use with molds recessed in this manner, and in many cases, particularly where the mold itself has a chilling effect on the molten metal, for example, in the case of green sand molds or molds embodying the invention described and claimed in my copending application, Serial No. 87,086, filed June 16, 1936, it may be more desirable to construct a complete unit which is merely clamped to the end of the mold with its opening 11' registering with the corresponding opening into the mold cavity.

This I have shown in Fig. 4. In this case the construction is similar to that of Figs. 1 to 3 excepting that the channel member 14a for the riser extends down as a complete mate for the channel member 15, thus making a pouring and riser unit complete in itself even before attachment to the mold. Such a unit may be used with plaster molds, with sand molds, with permanent molds or in any case where a gate and riser should otherwise be provided.

In Figs. 6 and 7, I have shown another embodiment of the invention wherein the connector between the riser and the mold cavity is in the form of a relatively long vertical slot 11b; and in this instance the partition 19b between the gate and riser is pierced at several points by openings 20, 20', 20''. Other parts shown in these figures are similar to those shown in Figs. 1 and 3 and are similarly numbered.

With many castings the design may be such that better results can be obtained by filling and feeding the mold cavity through a connector or connectors extending over a considerable distance. In such case it is very advantageous to use a series of openings as shown in Figs. 7 and 8. This enables the top parts of the casting to be filled with hot metal flowing directly through the upper opening or openings as the level of the metal rises in the mold, rather than by metal which has been cooled off by having first to flow through a lower opening. Thus the casting may be poured at substantially lower temperature without danger of the metal freezing off in the mold before the mold is entirely filled.

It will be obvious that by changing the number and position of the openings in the dividing partition it is possible to meet very easily the gating requirements of a great variety of casting designs. The rate of flow of the metal can be regulated by merely varying the size of the opening or openings in the partition. Funnels of a single design or a few standard designs and sizes can thus be used on a great range of applications.

In Figs. 9 and 10, I have shown two examples of the manner in which the invention may be adapted to plural castings. This arrangement has the further advantage that a single pouring funnel 15c or 15d may be connected directly to and arranged directly adjacent a plurality of molds arranged in a single unit with a plurality of risers for the several castings, or with a common riser communicating with the several molds, all of which may be poured in a single operation. By reason of the common gate or common riser and gate, the amount of metal required for casting is thus further reduced; and, by reason of the proximity of the several risers and central position of the gate and riser unit between the mold cavities, there is a greater economy of heat in gate and riser unit which permits a reduction in the volume of metal required for each riser, thus effecting still further economy.

Although I have shown only a fragment of each mold with a single gate and riser unit, it will be understood, of course, that for many castings gates and/or risers will be required at a plurality of positions distributed about the castings. It is an advantage of my invention that the standard units may be applied to openings at any or all of these positions and may serve as both gate and riser or as riser alone—i. e., metal may be poured into all or less than all of the units provided. Where the unit is used solely as a riser the central partition 19 may be omitted, as its function is not then required, although there is no objection to using the unit in exactly the same form as shown.

It will be obvious to anyone acquainted with gating practice that the relative proportions of the channels on the sides of the partition 19 may be varied somewhat according to the requirements of particular castings, and that no fixed ratio is necessary to effect the purposes of the invention. It will be advantageous, however, to keep the riser channel as large in proportion to the gate channel as is consistent with convenient and satisfactory pouring of the metal.

What I claim is:

1. A combined pouring gate and riser unit for casting molds which comprises a pair of channeled insulating members of refractory material adapted to fit together with the sides of their respective channels engaging one another, one of said members having its channel open at its upper end to form a pouring funnel, and the other of said channels having an opening near its lower end adapted to communicate with the cavity of a casting mold and of dimensions adapted to hold the metal thereof molten until after freezing of the metal in the mold, a longitudinal partition between said members adapted to separate their respective channels but having a low opening near its lower end through which molten metal may flow with a skimming action, and a jacket adapted to hold said members together and augment their mechanical strength.

2. A combined pouring gate and riser unit for casting molds which comprises a pair of channeled members of a calcined plaster of Paris composition adapted to fit together with the sides of their respective channels engaging one another, one of said members having its channel open at its upper end to form a pouring funnel, and the other of said channels having an opening near its lower end adapted to communicate with the cavity of a casting mold and of dimensions adapted to hold the metal there-

of molten until after freezing of the metal in the mold, a longitudinal partition of asbestos paper between said members adapted to separate their respective channels but having a low opening near its lower end through which molten metal may flow with a skimming action, and a jacket adapted to hold said members together and augment their mechanical strength.

3. A combination pouring gate and riser unit for casting molds which comprises a channel part of refractory thermal insulating material having an opening at its upper end adapted to receive molten metal poured therein and an opening near its lower end through which it communicates with a cavity of a casting mold to feed molten metal thereto and of dimensions adapted to hold the metal thereof molten until after freezing of the metal in the mold, and a longitudinal partition in the channel of said part dividing it longitudinally into a pouring gate and riser, said partition having low heat capacity and low heat conductivity and having a narrow opening near the bottom of said channel through which molten metal must pass in flowing to the mold cavity and the riser from the pouring gate.

4. In combination with a casting mold, a pouring gate, a riser close to said pouring gate, communicating therewith through a low opening adapted to skim molten metal flowing therethrough, and communicating with the mold cavity by an opening much larger than the skimming opening and of dimensions adapted to hold the metal thereof molten until after freezing of the metal in the mold, said riser and pouring gate being in close heat-exchange relation with one another and together insulated from external cooling.

5. A combined pouring gate and riser unit for casting molds which comprises a pair of channeled members adapted to fit together with the sides of their respective channels engaging one another, one of said members having its channel open at its upper end to form a pouring funnel, and the other of said channels having an opening near its lower end adapted to communicate with the cavity of a casting mold and of dimensions adapted to hold the metal thereof molten until after freezing of the metal in the mold, and a longitudinal partition between said members adapted to separate their respective channels but having a low opening through which molten metal may flow with a skimming action.

6. In combination with a casting mold, a combined gate and riser unit adjacent to said mold and comprising a channeled member having its upper end open for receiving molten metal and its lower end closed from the atmosphere but communicating with the interior of said mold through an opening of dimensions adapted to hold molten metal therein until after freezing of the metal in the mold, and a longitudinal partition at one side of the channel having at least one low opening therein through which metal may pass in its flow from said channel to the interior of the mold.

10 7. The combination as defined in claim 6, in which metal receiving cavities extend beyond the said opening on both sides of the partition, whereby heat of the metal around the opening tends to keep open a communication of liquid metal from side to side through such opening.

8. In combination with a casting mold, a combined riser and gate unit having a channel therein open at the top and provided with an opening for communicating with the mold, the shortest diameter of said opening being not substantially less than the thickness of the metal part to be cast thereby, and a thin perforated longitudinal partition of refractory sheet material dividing said channel longitudinally, whereby metal poured on one side of the partition as into a pouring gate is skimmed by flowing through said perforations before entering the casting mold.

9. In combination with a plurality of casting molds, a combined gate and riser unit adjacent to all of said molds and comprising a channeled member having therein a pouring channel common to said several molds open at the top to form a pouring gate and closed at the bottom, but having an opening communicating with the interior of each mold, said channeled member being positioned between and close to said molds, whereby the metal in said channel and openings may remain liquid until the metal in the casting has substantially solidified, and being divided by a tubular partition open at its upper end and having a low opening near its lower end, and spaced from the outer wall of said channeled member whereby to provide a peripheral riser surrounded by and communicating with the several molds.

50

MORRIS BEAN.
